G. C. MURPHY,
RELAY CONTACT DEVICE,
APPLICATION FILED JULY 30, 1913.

1,109,778.

Patented Sept. 8, 1914.

UNITED STATES PATENT OFFICE.

GEORGE C. MURPHY, OF LOUISVILLE, KENTUCKY.

RELAY CONTACT DEVICE.

1,109,778.

Specification of Letters Patent.

Patented Sept. 8, 1914.

Original application filed January 14, 1912, Serial No. 740,219. Divided and this application filed July 30, 1913. Serial No. 782,130.

To all whom it may concern:

Be it known that I, GEORGE C. MURPHY, citizen of the United States, residing at Louisville, in the county of Jefferson and State of Kentucky, have invented certain new and useful Improvements in Relay Contact Devices, of which the following is a specification, reference being had therein to the accompanying drawing.

10 This invention relates to circuit closing devices of the solenoid type and has for its object the production of an efficient means for closing an electric circuit when the solenoid is energized, and is especially 15 adapted for use in connection with electric railway signals as specifically defined in my copending application filed January 14th, 1912, Serial Number 740,219, of which the present case is a divisional application.

20 Another object of the invention is the production of a simple and efficient contact means of the solenoid type which consists of a minimum number of parts.

With the above and other objects in view 25 this invention consists of certain novel combinations, constructions, and arrangements of parts as will be hereinafter fully described and claimed.

In the accompanying drawings:—Figure 1 30 is a front elevation of the solenoid for closing the desired electric circuits connected thereto. Fig. 2 is a central vertical section through the solenoid illustrated in Fig. 1. Fig. 3 is an enlarged side elevation partly 35 in section of one of the contact shoes for operating with the solenoid illustrated in Fig. 1. Fig. 4 is an edge view of the structure illustrated in Fig. 3 showing the same mounted upon a support. Fig. 5 is a detail 40 perspective of the supporting arm for the contact shoes. Fig. 6 is a central longitudinal section through the supporting arm and supporting shaft for the contact shoe.

45 By referring to the drawings it will be seen that the present invention consists of a solenoid adapted to be used in connection with electric railway signals as above described, and this device may be placed in any desired position upon the body of the 50 car. The solenoid is preferably mounted upon a casing 4, and comprises a magnet 5 having a metal core 6. This core is provided with a pair of contact collars 7 formed thereon in spaced relation and is also provided with a pair of collars 8 which are

adapted to limit the longitudinal movement of the cores 6 relative to the magnet 5. A bracket 9 is carried by the casing and is provided with an insulated aperture 10 through which works the reduced end 11 of 60 the core 6. A plug 12 is carried by the protector shield 13 and constitutes a stop for the core or plunger 6. Binding posts 14 are mounted upon the casing 4 so as to electrically connect the magnet with the source 65 of electrical supply. A plurality of posts 15 are supported within the casing 4 upon supporting bolts 16 and these posts 15 carry at their outer ends shoes 17. The posts 15 are also provided with laterally extending 70 ends 18, which laterally extending ends are provided with outwardly extending spaced ears 19 between which fit the laterally extending fingers 20 of the shoes 17.

A spring 21 is interposed between one of 75 the ears 19 and the laterally extending fingers 20 so as to normally exert an outward pressure upon the shoes 17. This spring 21 also projects under the finger 20 and engages the under face of the shoe 17 as indicated 80 clearly in Fig. 1 so as to add additional outward pressure upon the shoes. Each of the shoes 17 is provided with a curved outer face 22 for facilitating the engagement of the collars 7 of the core or plunger 6 with 85 the shoes as the collars are brought into engagement therewith. It will be seen that these springs 21 will normally hold the shoes in firm contact with the collars 7.

Of course, the usual lead wires may be 90 connected to the several contact shoes for the purpose of conveying the current to the desired points.

The operation of the device is as follows: 95 As the magnet 5 is energized the core 6 will be drawn upwardly, thereby causing the collars 7 to be brought into contact with the contact shoe 17 and close an electrical circuit therethrough. The contact shoes 17 will be limited in their upward swinging 100 movement owing to the fact that the laterally extending fingers 20 thereof will engage one of the spaced ears 19 and prevent the further upward swing of the shoes 17. It should be understood, however, that as 105 soon as the magnet 5 is deenergized, the weight of the core 6 will cause the same to drop downwardly, and this downward movement will not be resisted by means of the shoes 17 engaging the collar 7 for the reason. 110

that the shoes 17 may yield slightly downwardly to allow the collars 7 to be released from the core 6. The spring 21, however, will cause the shoes 17 to retain their normal position and at all times hold these shoes in a position to be readily engaged by the collar 7.

It should be understood that the purpose of the present invention is to close a circuit 10 through the contact shoes 17 by the energization of the magnet 5.

Having thus described the invention what is claimed as new, is:—

A relay contact shoe for a relay device 15 of the class described comprising a body provided with a curved contact point, a supporting post, said supporting post provided with a laterally extending portion provided with a pair of outwardly extending

spaced ears, said shoe provided with a 20 laterally extending finger adapted to swing between said spaced ears, a spring interposed between one of said ears and passing around said laterally extending finger for normally exerting a downward pressure 25 upon said finger and allowing said shoe to have a yieldable inward swing, said spring provided with an upwardly bent end portion for engaging one of said ears and holding said spring against accidental displacement therefrom.

In testimony whereof I hereunto affix my signature in presence of two witnesses.

GEORGE C. MURPHY.
